UNITED STATES PATENT OFFICE.

CHARLES T. HOWELL, OF GLEN FLORA, WISCONSIN.

FENCE-POST.

957,677.

Specification of Letters Patent. Patented May 10, 1910.

Application filed June 26, 1908. Serial No. 440,485.

To all whom it may concern:

Be it known that I, CHARLES T. HOWELL, a citizen of the United States, and a resident of Glen Flora, in the county of Rusk 5 and State of Wisconsin, have invented a new and Improved Fence-Post, of which the following is a full, clear, and exact description.

My invention relates to fence posts, and 10 more particularly to such as are constructed of a series of concrete blocks devoid of sharp angles and preferably spherical in form, arranged one above the other, and held in vertical alinement by a connecting 15 rod which extends through registering openings in the spheres.

The object of the invention is to provide a device of the class described, which has a certain degree of flexibility due to its construction, and which is less easily affected 20 by frost or wear than the ordinary concrete post.

The invention consists in the construction and combination of parts to be more fully 25 described hereinafter and particularly set forth in the claims.

Reference is to be had to the accompanying drawings forming a part of this specification, in which similar characters of reference 30 indicate corresponding parts in all the views.

Figure 1 is a side elevation of an embodiment of my invention; Fig. 2 is a sectional view showing the means employed for holding 35 the spheres in vertical alinement; and Fig. 3 is an enlarged transverse section showing one of the brackets used for supporting the fence wires.

Before proceeding to a more detailed description of my invention, it should be understood that I provide a fence post preferably 40 constructed of a series of spherical, concrete blocks held in vertical alinement by a connecting rod, which extends through 45 their centers. Any suitable number of brackets for carrying the fence wires may be arranged on the connecting rod intermediate of two adjacent spheres. This construction is flexible, and is of great advantage 50 in fencing in cattle lands, as the chance

of a post being knocked down, or the wires becoming broken, is greatly lessened owing to the flexibility of the whole structure. Further, as the blocks are spherical, they are less easily injured by frost or weather 55 conditions. Furthermore, for shipping, the device can easily be reduced to its component parts.

Referring more particularly to the drawings, I provide a series of spherical blocks 60 1, of any suitable material, such as concrete or the like, and having openings 2 extending through the centers thereof. I further provide a connecting rod 3 adapted to be arranged in the openings 2 of the spheres, 65 to hold the latter in vertical alinement. The connecting rod 3 has both ends 4 suitably threaded to receive adjusting nuts 5, which secure the spheres in place. Arranged on the connecting rod between two 70 adjacent spheres are substantially U-shaped brackets 6, having one end 7 elongated and projecting beyond the spheres. This end has an opening 8 therethrough, for carrying the fence wires 9. The bracket further has 75 two curved, inwardly projecting extensions 10 which serve to engage the connecting rod 3. A locking bolt 11 extends through the sides of the bracket adjacent to the extensions 10 and carries a nut 12. This locking 80 bolt serves to secure the extensions of the bracket firmly against the connecting rod.

Having thus described my invention, I claim as new and desire to secure by Letters Patent:

1. In a device of the class described, a series of spheres having openings therethrough, a rod traversing the openings, clamps arranged at spaced intervals on the rod, and between adjacent spheres, and nuts 85 threaded on the ends of the rods for securing the parts together.

2. In a device of the class described, a series of spheres having openings therethrough, a rod traversing the openings, and 90 means engaging the ends of the rods for retaining the spheres in place.

3. In a device of the class described, a series of spheres having diametrical openings, and arranged in superimposed relation with 100

the openings in alinement, a rod passing through the alined openings, and extending beyond the spheres at each end, clamps arranged at spaced intervals on the rod between adjacent spheres, and nuts threaded onto the extended ends of the rod.

5 In testimony whereof I have signed my

name to this specification in the presence of two subscribing witnesses.

CHARLES T. HOWELL.
